No. 637,159.

Patented Nov. 14, 1899.

S. G. RAYL.

COVER FOR HAYSTACKS.

(Application filed May 19, 1899.)

(No Model.)

UNITED STATES PATENT OFFICE.

SAMUEL GARRET RAYL, OF TUNIS, IOWA.

COVER FOR HAYSTACKS.

SPECIFICATION forming part of Letters Patent No. 637,159, dated November 14, 1899.

Application filed May 19, 1899. Serial No. 717,457. (No model.)

To all whom it may concern:

Be it known that I, SAMUEL GARRET RAYL, of Tunis, in the county of Wapello and State of Iowa, have invented a new and Improved 5 Cover for Haystacks, of which the following is a full, clear, and exact description.

The purpose of this invention is to provide a sectional cover for haystacks, the sections of which may be adjusted to form a cover of 10 any size desired and by means of which the stacks or ricks may be effectively protected.

This specification is the disclosure of one form of the invention, while the claims define the actual scope thereof.

15 Reference is to be had to the accompanying drawings, forming a part of this specification, in which similar characters of reference indicate corresponding parts in all the views.

Figure 1 is an end elevation of the device 20 in use. Fig. 2 is a bottom plan of the invention with several of the sections assembled, and Fig. 3 is a fragmentary view of the same sections dissociated.

The device may be constructed of wood or 25 metal or a combination of both, as desired.

In the drawings I have illustrated three sections A, B, and C. The section A is the end section and the sections B and C are intermediate sections, it being understood that 30 another section A is in practice to be used at the end of the cover opposite that to which the end section A is shown applied in the drawings. One end section A is provided for the roof, and the number of intermediate sections B and C employed depends upon the 35 size of the rick or stack to be covered. The section A has a frame formed of two arched strips 4, extending parallel with each other and transversely with respect to the roof. To 40 these strips 4 the roof proper, 5, is fastened. The strips 4 are rigidly joined by stringers 6, and the stringers 6 are fastened at their ends by strips 7, similar to the strips 4 and running, respectively, alongside thereof. By this construction the strips 4 and 7 are separated from 45 each other for a distance equal to the thickness of the stringers 6, the whole structure being rigid, as shown. The intermediate or other sections B and C have strips 4^a, similar 50 to the strips 4 and carrying the roof proper, 5^a. Stringers 6^a are fastened to the strips 4^a and are arranged similarly to the strips 6, except

that the strips 6^a are extended past the side of the section for a distance equal, approximately, to the width of the roofing proper, 5^a. 55 The stringers 6^a are connected with strips 7^a, similar to the strips 7 and arranged in the same manner.

The stringers 6^a in the sections B and C are arranged out of longitudinal alinement with 60 each other, as indicated in the drawings, so that the extended ends of the stringers 6^a may be moved between the strips of the adjacent sections in the manner shown in Fig. 2, thus snugly connecting all of the sections and forming 65 a complete cover. For the purpose of making the parts 5 and 5^a fit snugly in the contiguous section, as shown in Fig. 2, the parts 5^a are formed with bent edges 5^b, serving to overlap the contiguous edges, as illustrated. This makes a secure and weather-tight 70 connection. The sections are arranged to be friction-tight when engaged, so that no latching devices are necessary.

When the device is in use, it is arranged as 75 shown in Fig. 1, and it may be held in place by means of lines 8, which may be anchored to the ground or attached to weights or held in any other manner desired.

Having thus described my invention, I 80 claim as new and desire to secure by Letters Patent—

1. A temporary roof, formed of separable sections provided with stringers projected beyond one of the sections and respectively running 85 in planes immediately adjoining the planes of the stringers of the other sections, and having lateral engagement with the stringers of said other sections.

2. A temporary roof, having a number of 90 separable sections, each section having a roof proper, strips attached to the roof proper, and stringers fastened between the strips, the stringers of one section being projected beyond the same and respectively running in 95 planes immediately adjoining the planes of the stringers of the other section, and having lateral engagement with the stringers of the said other section.

SAMUEL GARRET RAYL.
